US010081918B2

(12) **United States Patent**
Browning et al.

(10) **Patent No.:** **US 10,081,918 B2**
(45) **Date of Patent:** ***Sep. 25, 2018**

(54) **PAVING STONES**

(71) Applicant: **Oldcastle Architectural, Inc.**, Atlanta, GA (US)

(72) Inventors: **Leonard Browning**, Aurora, IL (US); **Robert J. Lundell**, Stillwater, MN (US)

(73) Assignee: **Oldcastle Architectural, Inc.**, Atlanta, GA (US)

(*) Notice: Subject to any disclaimer, the term of this patent is extended or adjusted under 35 U.S.C. 154(b) by 0 days.

This patent is subject to a terminal disclaimer.

(21) Appl. No.: **15/808,403**

(22) Filed: **Nov. 9, 2017**

(65) **Prior Publication Data**

US 2018/0066403 A1 Mar. 8, 2018

Related U.S. Application Data

(63) Continuation of application No. 15/093,474, filed on Apr. 7, 2016, now Pat. No. 9,840,813, which is a continuation of application No. 14/056,220, filed on Oct. 17, 2013, now Pat. No. 9,315,950.

(60) Provisional application No. 61/716,033, filed on Oct. 19, 2012.

(57) **ABSTRACT**

Generally L-shaped, square, rectangular, triangular, hexagonal, parallelogram and other-shaped paving stones with inter-fitting vertical spacers forming serpentine side contact surfaces that provide enhanced stone-to-stone interlocking in both water-permeable and water-impermeable paving installations.

PAVING STONES

**CROSS REFERENCE TO RELATED
APPLICATION**

This application is a continuation of U.S. patent application Ser. No. 15/093,474 filed Apr. 7, 2016, which is a continuation of U.S. patent application Ser. No. 14/056,220 filed Oct. 17, 2013, issued as U.S. Pat. No. 9,315,950 on Apr. 19, 2016, which claims priority to U.S. Provisional Patent Application Ser. No. 61/716,033 for "Paving Stones" filed Oct. 19, 2012, Len Browning and Robert J. Lundell, inventors, the contents of all of which are incorporated herein by reference in their entireties.

FIELD OF THE INVENTION

This invention relates to paving stones and blocks, natural and manmade.

BACKGROUND

Paving stones have been in use for thousands of years. Initially such stones were literally that, naturally occurring stones or rocks of various shapes and compositions. Even the earliest installers of such stones recognized that stones of regular shapes and sizes facilitated their installation and effectiveness in use. That doubtless led initially to care in selecting stones and placing them and later to preparatory shaping of stones to facilitate their installation and function. Eventually such regular shapes came to be embodied in man-made bricks and "stones," including a variety of different shapes and compositions.

Notwithstanding thousands of years of human experience in paving a variety of different surfaces for a variety of different reasons and uses, the need continues for pavers that can better address certain requirements.

Among those requirements are the need to successfully transfer the load of vehicles that use the paving to the subgrade without damaging the base course or its stability.

As is explained by the ICPI Tech SPEC Number 1 (Glossary of Terms for Segmental Concrete Pavement), interlocking concrete pavement is a system of paving that consists of discrete, hand-sized paving units with either rectangular or dentated shapes manufactured from concrete. The units are placed in an interlocking pattern, compacted into coarse bedding sand, the joints filled with sand and compacted again to start interlock.

Interlocking results when frictional forces between paving units prevent them from rotating, or moving horizontally or vertically in relation to each other. Interlocking is also defined as the inability of a concrete paver to move independently of its neighbors. Friction forces enable load transfer among the paving units. There are three kinds of load transfer, vertical interlock, horizontal interlock and rotational interlock. Vertical interlock is achieved by shear transfer of loads to surrounding units through sand in the joints. Horizontal interlock is primarily achieved through the use of laying patterns that disperse forces from braking and accelerating vehicles. Rotational interlock is achieved by using pavers of sufficient thickness, placed closely together, and restraining them by a stationary edge such as a curb.

Interlocking is not, however, the only characteristic of concern. Many paver installations need to accommodate the flow of water through the paved surface and into underlying structures, installations of which pavers are sometimes referred to as permeable interlocking concrete pavement.

2

Likewise, it is important the pavers be attractive, easy to install manually or with mechanical systems, and that they be easy to manufacture economically, quickly and reliably without undue complexity in the manufacturing equipment and without undue difficulty associated with wear of the manufacturing equipment.

SUMMARY

10 The terms "invention," "the invention," "this invention" and "the present invention" used in this patent are intended to refer broadly to all of the subject matter of this patent and the patent claims below. Statements containing these terms should be understood not to limit the subject matter described herein or to limit the meaning or scope of the 15 patent claims below. Embodiments of the invention covered by this patent are defined by the claims below, not this summary. This summary is a high-level overview of various 20 aspects of the invention and introduces some of the concepts that are further described in the Detailed Description section below. This summary is not intended to identify key or 25 essential features of the claimed subject matter, nor is it intended to be used in isolation to determine the scope of the claimed subject matter. The subject matter should be understood by reference to appropriate portions of the entire specification of this patent, any or all drawings and each claim.

30 The pavers of this invention are attractive, easy and inexpensive to manufacture and install and can be assembled into strong paver systems that achieve good vertical, horizontal and rotational interlocking, balanced with substantial permeability to allow water to drain through such systems into underlying structures.

35 Pavers of this invention may be made in a number of different shapes, usually generally (a) square, (b) rectangular, (c) triangular, or (d) that can be thought of as combinations of squares, rectangles and triangles (such as L-shaped and parallelogram-shaped stones). The pavers of this invention may also be made in other shapes such as hexagons.

40 Significantly, the vertical walls of these pavers include "serpentine," "sinuous," "wavy," "saw tooth," "sinusoidal" or "crenulated" portions (when viewed in plan or "from above") that are positioned to inter-fit with like-shaped 45 portions of other pavers of this system in assemblies of pavers. (The term "serpentine" will generally be used in this patent to mean all of the above and other appropriate terms for wall portions of the general shapes described and depicted herein).

45 These serpentine wall portions contact abutting paver wall portions to maintain desired separation between pavers to permit vertical water flow when desired. Moreover, the serpentine wall portions providing superior frictional vertical interlocking, as well very effective horizontal and rotational interlocking between pavers. These serpentine wall portions are easier to produce and more durable than more angular side wall shapes. Superior frictional interlocking enables pavers of particular geometries and dimensions to accommodate more water flow because there is relatively 50 more room for vertical water flow channels.

55 While serpentine wall portions can be used with numerous other paver shapes such as hexagons, among others, they are well-adapted for use with pavers that are rectangles, 60 including squares, or combinations of rectangles, such as L-shaped pavers, triangles, parallelograms and combinations of triangles and rectangles.

BRIEF DESCRIPTION OF THE DRAWINGS

Illustrative embodiments of the present invention are described in detail below with reference to the following drawing figures:

FIG. 1 is an isometric view of a generally L-shaped embodiment of a paving stone of the this invention.

FIG. 2 is a top plan view of two abutting L-shaped stones like the one shown in FIG. 1.

FIG. 3 is a top plan view of one embodiment of a mold pallet layout of L-shaped stones like those shown in FIG. 1.

FIG. 4 is a top plan view of an arrangement of several different paving, stone embodiments of this invention.

FIG. 5 is a model of a paving stone edge shape illustrating the length of contacting faces with an exemplary serpentine block edge shape.

FIG. 6 is an enlarged fragment of FIG. 5 taken at circle "6."

FIG. 7 is a horizontal cross section of the stone of FIG. 1.

FIG. 8 is an enlarged fragment of FIG. 7 taken at circle "8."

FIG. 9 is a view similar to FIG. 1 with a "sinuous" or "serpentine" portion of the paver wall projected and flattened to show its greater effective contact area.

FIG. 10 depicts an alternative embodiment of the pavers of this invention with abutting walls for substantially water impermeable paving installations.

FIG. 11 depicts a top plan view of hexagonal paving stone of this invention.

FIG. 12 is a top plan view of an assembly of hexagonal stone like the stone of FIG. 11.

DETAILED DESCRIPTION

The subject matter of embodiments of the present invention is described here with specificity to meet statutory requirements, but this description is not necessarily intended to limit the scope of the claims. The claimed subject matter may be embodied in other ways, may include different elements or steps, and may be used in conjunction with other existing or future technologies. This description should not be interpreted as implying any particular order or arrangement among or between various steps or elements except when the order of individual steps or arrangement of elements is explicitly described.

FIGS. 1 and 2 depict an L-shaped paving stone 10 having false joints 12 that look like the full joints 14 visible in FIG. 2 to create an installed pattern appearing to be made of square pavers 16. Each stone 10 has side walls 18 and spacers 20 with curved cross-section crowns 22. Spacers 20 serve at least two purposes. First, they separate stones 10 in a pavement installation so that (a) there are vertical channels 17 between stones 10 that can "filled" with clean, open graded fine aggregate and through which water can flow and (b) stones 10 will be uniformly spaced and aligned in paving installations. Second, the spacers provide interlocking contact surfaces 21 between tiles that interlock the stones 10 vertically, horizontally and rotationally.

As may be appreciated by reference to FIG. 2, arrangements of L-shaped stones 10 with the square paver units 16 oriented in rows and columns will result in inter-fitting of spacers 20 with the crown or furthest protruding portion 22 of spacers 20 on one stone 10 in contact with the side walls 18 of an adjacent stone 10.

FIG. 8 provides an enlarged fragment showing an exemplary spacer 20 geometry and dimensions, but other geometries and dimensions are also possible. The tops 9 of spacers

20 can be square to the spacer 20 and paver walls 18, but a sloping transition as depicted in the drawings typically is easier to manufacture and more durable in transportation, placement and use. In embodiments of this invention depicted in the drawings, (apart from the spacer top or transition 9) each spacer has two planer surfaces joined to each other by a curved or crown surface 22. Utilizing the geometry and dimensions depicted in the figures for spacers 20 (with spacers 20 projecting or protruding from walls 18 about one-third inch (specifically, for instance, projecting 0.336 inches (8.53 mm)) will provide spacing (15 on FIG. 2) of approximately $\frac{1}{4}$ to $\frac{3}{8}$ inch between opposed walls 18 in assemblies of L-shaped blocks 10.

Use of spacer 20 walls 11 at an inside angle relative to the plane of wall 18 of approximately 45 degrees and, therefore, at an outside angle relative to the plane of wall 18 of approximately 135 degrees (so that the two spacer walls 11 of each spacer 20 are separated by approximately 90 degrees from each other) is beneficial and therefore desirable. For instance, use of the curved crown 22 and the planar wall angles described here makes the spacers easy to form and durable in manufacture, shipment, placement and use. However, other angles could also be used, and other shorter or longer radii than the radius of approximately 0.4 inches or less (about 10 mm or less) shown in FIG. 8 could be used.

As may be appreciated by reference to FIG. 7, the locations of spacers 20 on opposite walls of L-shaped pavers 10 are offset from each other by one-half of the distance between adjacent spacers 20 on each paver 10. This facilitates the inner-fitting of spacers 20 on abutting pavers 10 (illustrated in FIGS. 2, 4 and 9). The illustrated arrangement of pairs of spacers 18 result in automatic inter-fitting of spacers in substantially all practical arrangements of L-shaped blocks 10.

Alternative sizes and shapes of pavers are shown in FIG. 4, which includes small square pavers 22, large square pavers 24, large rectangular pavers 26, small rectangular pavers 28, small triangular pavers 29, large triangular pavers 31 and parallelogram pavers 33. Hexagonal pavers 37 are shown in FIGS. 11 and 12. As is depicted in FIGS. 4 and 12, the narrow rectangular pavers 28 have room for only one spacer 20 one each paver 28 end 35 using spacers 20 of the size and locations depicted in the drawings. As is clear from the Figures, particularly including FIG. 4, this invention may be embodied in pavers having a number of different general shapes. For simplicity only, however, much of the description herein focuses on and describes an exemplary L-shaped paver 10. The embodiments of the present invention and the following patent claims should not be understood to be limited to L-shaped pavers or any other particular paver shape unless a description or claim explicitly contains such a limitation.

As mentioned above, vertical interlocking between paving stones is achieved by shear transfer of loads to surrounding units. This occurs as a result of contact between the sides of pavers and through coarse sand or other aggregated in the joints between the opposed sides of closely spaced pavers. Some horizontal interlocking occurs for the same reason, but the laying pattern of pavers and interlocking between pavers also contribute to horizontal interlocking.

The "serpentine," "sinuous," "wavy," "saw tooth," "sinusoidal" or "crenulated" portions of the side walls of the pavers of this invention provide enhanced vertical interlocking because they increase and optimize the surface areas of abutting pavers that are in contact with each other (directly or through coarse sand or other aggregate in the joints). Simply stated, more surface contact (for a given side wall

portion), better resists relative vertical movement between adjacent stones, and this results in greater vertical interlocking. The surface interface between abutting pavers 10 of this invention is not a plane (as would be the case with flat walls) but is an undulating or wavy surface.

Horizontal interlocking occurs as a result of similar contact between the sides of pavers and through coarse sand or other aggregate in the joints between the opposed sides of closely spaced pavers. Significantly, horizontal interlocking also occurs in the interlocking structure of the side walls 18. Force applied horizontally tending to cause relative horizontal movement between abutting stones is resisted by friction and by the protruding ridges 20 that transfer force from the ridges 20 on one paver 10 to the ridges 20 on an abutting paver 10.

FIGS. 5 and 6 facilitate description of these reasons that enhanced interlocking may be achieved in embodiments of this invention. FIG. 5 depicts a hypothetical square paver 30 that has spacers 20 that are shown (on the top and right sides) inter-fitted with other spacers 20 on a second square paver 32. The "contact path" 34 (that is, an "edge view" of a contact surface between pavers) is illustrated, together with a hypothetical "straight line" contact path 36. As can be easily seen by comparison of these lines 34 and 36, the serpentine path is longer. For a 12 inch square paver 30 with the spacer 20 shape and geometry illustrated in the figures and described above, the serpentine path has been calculated to be 8.62% longer than the straight line path 36, which means an 8.62% larger contact surface. Such a larger, sinusoidal, wavy or undulating contact surface 38 is depicted in FIG. 9 as if separated from the stone 10 and is compared to a flat surface 40 occupying the same portion of the stone 10 wall 18 as the undulating surface 38. If undulating surface 38 is "flattened," it is the same height but is wider and therefore a larger surface 42. Thus the vertically-extending straight, horizontally-extending serpentine contact surface contact surface 38 provides a greater contact area for a given width of paver 10 wall 18. This reduction in the portion of the side that needs to be used in interlocking permits a larger area where the facing walls 18 are separated. At the same time it provides enhanced interlocking, a vertically-extending straight, horizontally-extending serpentine surface shape permits and facilitates formation of the pavers 10 using conventional paver-making equipment and likewise facilitates relative vertical movement of pavers 10 in placement or removal of the pavers.

As a consequence of the capacity for achieving acceptably significant interlocking utilizing the serpentine shapes described above, greater portions of a particular side wall 18 can be straight and separated from the opposing side wall 18 of an adjacent block, thereby providing greater areas 17 (see FIG. 2) and greater capacity for flow of water down between the opposed side walls 18 and into underlining structure in a paving system designed to permit water infiltration.

If embodiments of the pavers 10, 19, 24, 26, 28, 29, 31, 33 and 37 of this invention are to be used in installations where water infiltration is not needed, as is illustrated in FIG. 10, opposed portions of the walls 17 of pavers 50 can abut at 52 (with space for coarse concrete sand), thereby enhancing frictional interlocking of the pavers because of the greater wall contact. Additional spacers 20 could also be used to further enhance interlocking since areas with wide gaps for water infiltration are not needed.

The design of the spacer 20 of this invention permits the produced products to grow slightly in size as a result of wear of the manufacturing molds and, in effect, adjust to the enlarged units without creating interferences because the

interfacing block shapes are forgiving and can be simply scaled up or down without changing block to block relationships.

In addition to increased frictional area between abutting pavers as a result of the serpentine frictional area, the projecting spacers resist relative motion of pavers horizontally because the projecting spacers 20 act as "stops" resisting such relative movement.

Different arrangements of the components depicted in the drawings or described above, as well as components and steps not shown or described are possible. Similarly, some features and subcombinations are useful and may be employed without reference to other features and subcombinations. Embodiments of the invention have been described for illustrative and not restrictive purposes, and alternative embodiments will become apparent to readers of this patent. Accordingly, the present invention is not limited to the embodiments described above or depicted in the drawings, and various embodiments and modifications can be made without departing from the scope of the claims below.

That which is claimed is:

1. A concrete paver for use in combination with other like pavers, the paver comprising:
  - (a) top and bottom horizontal surfaces;
  - (b) six vertical walls forming an L-shape; the six vertical walls including first and second long vertical walls perpendicular to each other, and the remaining four of the vertical walls being shorter than the first and second long vertical walls;
  - (c) a plurality of identical spacers projecting from the vertical walls, at least one spacer projecting from each of the vertical walls;
    - (i) each of the vertical walls having at least 2 aligned straight sections with the at least one spacer between the straight sections;
    - (ii) each of the long vertical walls having at least 3 aligned straight sections;
    - (iii) each long vertical wall having at least one spacer pair; each spacer pair having two spacers separated by one of the straight sections a first distance sized to receive a spacer from an adjacent like paver to interlock the pavers; the first distance being shorter in length than all other straight sections that are not between the spacers in a spacer pair;
    - (iv) each spacer having two angled, straight walls converging as they extend away from the straight sections and joined by a crown surface.
2. The paver of claim 1 wherein each crown surface is curved.
3. The paver of claim 1 wherein each of the first and second long vertical walls has two spacer pairs.
4. The paver of claim 1 further comprising:
  - (a) a first false joint having an appearance of a full joint extending between the first long vertical wall and one of the shorter vertical walls;
    - (i) the first false joint being parallel to the second long vertical wall;
  - (b) a second false joint having an appearance of a full joint extending between the second long vertical wall and another of the shorter vertical walls;
    - (i) the second false joint being parallel to the first long vertical wall.
5. The paver of claim 4 wherein:
  - (a) the first and second false joints do not align with any of the spacers.

6. The paver of claim 1 wherein:

- (a) at least some of the shorter vertical walls have at least one spacer pair and at least 3 aligned straight sections with one spacer between each adjacent pair of straight sections;
- (i) each spacer pair having two spacers separated by one of the straight sections a first distance sized to receive a spacer from an adjacent like paver to interlock the pavers.

7. The paver of claim 6 wherein each of the shorter vertical walls has at least one spacer pair.

8. The paver of claim 1 wherein the paver comprises dry cast concrete.

9. The paver of claim 1 wherein a top of each of the spacers has a sloping transition from the paver top surface.

10. The paver of claim 1 wherein the top and bottom horizontal surfaces are parallel and planar.
